US00D776735S

(12) **United States Design Patent** (10) Patent No.: **US D776,735 S**
(45) Date of Patent: **** Jan. 17, 2017**

(54) **INDUSTRIAL ROBOT**

(71) Applicant: **ABB TECHNOLOGY LTD.**, Zurich (CH)

(72) Inventors: **Zhu Zhu**, Shanghai (CN); **Yongzhi Huang**, Shanghai (CN); **Tao Feng**, Shanghai (CN); **Xiaodong Cao**, Shanghai (CN); **Hui Yu**, Shanghai (CN); **Kaiyuan Cao**, Shanghai (CN); **Jingjing Zhou**, Shanghai (CN)

(73) Assignee: **ABB TECHNOLOGY LTD.**, Zurich (CH)

(**) Term: **14 Years**

(21) Appl. No.: **29/496,594**

(22) Filed: **Jul. 15, 2014**

(30) **Foreign Application Priority Data**

Mar. 28, 2014 (CN) 2014 3 0069043

(51) LOC (10) Cl. **15-99**

(52) U.S. Cl.

USPC **D15/199**

(58) **Field of Classification Search**

USPC D15/199; D21/578
See application file for complete search history.

(57) **CLAIM**

The ornamental design of an industrial robot, as shown and described.

DESCRIPTION

FIG. 1 is a first embodiment, showing a front view of an industrial robot of the new design;

FIG. 2 is a back view of the first embodiment;

FIG. 3 is a left view of the first embodiment;

FIG. 4 is a right view of the first embodiment;

FIG. 5 is a top view of the first embodiment;

FIG. 6 is a bottom view of the first embodiment;

FIG. 7 is a perspective view of the first embodiment;

FIG. 8 is a second embodiment, showing a front view of an industrial robot of the new design;

FIG. 9 is a back view of the second embodiment;

FIG. 10 is a left view of the second embodiment;

FIG. 11 is a right view of the second embodiment;

FIG. 12 is a top view of the second embodiment;

FIG. 13 is a bottom view of the second embodiment; and,

FIG. 14 is a perspective view of the second embodiment.

Any broken line(s) shown are for illustrative purposes only and form no part of the claimed design.

1 Claim, 12 Drawing Sheets
